UNITED STATES PATENT OFFICE.

LADISLAV F. KRISTUFEK, OF CHICAGO, ILLINOIS, ASSIGNOR TO TAYLOR E. BROWN AND CLARENCE E. MEHLHOPE, OF CHICAGO, ILLINOIS, COPARTNERS AS FIRM OF BROWN & MEHLHOPE.

MAGNETO-OPERATING MECHANISM.

1,120,315.

Specification of Letters Patent.

Patented Dec. 8, 1914.

Application filed December 1, 1911. Serial No. 663,292.

To all whom it may concern:

Be it known that I, LADISLAV F. KRISTUFEK, a subject of the Emperor of Austria-Hungary, residing at Chicago, in the county 5 of Cook and State of Illinois, have invented a new and useful Improvement in Magneto-Operating Mechanism, of which the following is a specification.

My invention relates to mechanism for 10 driving a magneto from an internal-combustion engine in connection with which the magneto is used for producing the current used in effecting ignition of the charges in the engine, and, more particularly, to the 15 type of mechanism of the character stated which operates to produce momentary acceleration of the rotary member of the magneto when the shaft of the engine from which it is driven is operating slowly, there- 20 by supplying to the ignition devices of the engine a current of high intensity for insuring the ignition of the charges introduced into the cylinder, or cylinders, of the engine.

My objects, generally stated, are to pro- 25 vide a novel and simple construction of mechanism of the character referred to which shall be positive in operation, insure the production of the required current for readily starting the engine from the magneto and running it from the latter at low speed, be automatically operative to effect corresponding actuation of the rotary member of the magneto relative to the engine-shaft when the latter reaches a predetermined speed, and shall be so constructed 30 that vibration, jarring and wear of the parts of the mechanism shall be reduced to the minimum.

Referring to the accompanying draw- 40 ings—Figure 1 is a view in vertical sectional elevation of a magneto, an engine-driven shaft, mechanism constructed in accordance with my invention for driving the magneto-armature from said shaft, and a distributor 45 for distributing the current generated by the magneto to the sparking-devices of the engine-cylinders (not shown), the section being taken at the lines 1 on Figs. 4 and 5. Fig. 2 is a section taken at the line 2 on Fig. 1 and viewed in the direction of the arrow. Fig. 3 is a section taken at the line 3 on Fig. 1 and viewed in the direction of

the arrow. Fig. 4 is a plan sectional view of the mechanism through the medium of which the magneto-armature is operated, the section line for the casing being indicated at 4 on Fig. 1. Fig. 5 is a section taken at the line 5 on Fig. 1 and viewed in the direction of the arrow. Fig. 6 is a sectional view of a portion of the mechanism shown in Fig. 2, the section being taken at a line corresponding to the line 2 on Fig. 1 and viewed in the direction of the arrow, this view showing the parts in a different position from that shown in Fig. 2. Fig. 7 is a view similar to Fig. 5 of the mechanism therein shown, illustrating this mechanism in a position corresponding to the position shown in Fig. 6. Fig. 8 is a view similar to Fig. 5 of the mechanism 70 therein shown, showing the position that the parts illustrated assume when the engine is operating sufficiently fast to automatically move the magneto-armature-retarding and accelerating mechanism out of 75 operating position. Fig. 9 is a perspective view of one of the magneto-driving elements rigid with the magneto-armature. Fig. 10 is a similar view of a cam-device employed. Fig. 11 is a similar view of a rock-device which co-operates with said cam; and Fig. 12, a similar view of toggle-mechanism connected with the armature of the magneto and through the medium of which the movement of the latter is intermittently retarded relative to the driving means there- 80 for and in opposition to the action of elastic mechanism.

I have chosen for the purposes of illustration a mechanism, embodying my invention, 90 for use in connection with a four-cylinder, four-cycle engine, the driving element of the mechanism for actuation from the engine-shaft being geared to the distributor in the ratio of two to one, and being adapt- 95 ed to be driven from the engine-shaft at the same speed as the latter, though it will be understood that my invention may be utilized in any other internal-combustion engine regardless of the type thereof and the 100 number of cylinders employed.

In the construction illustrated, a magneto is shown at 13, the field magnets and armature of which are represented at 14 and

15, respectively. A rotatable shaft through the medium of which the magneto-armature 15 is adapted to be driven, is represented at 16, this shaft, in practice, being driven from 5 the drive-shaft of an internal-combustion engine the ignition system of which is supplied with electric current from the magneto, the speed at which this shaft is driven relative to the engine-shaft depending upon 10 the type of engine to be supplied with electric current from the magneto, as is well understood in the art. The shaft 16 is rotatably mounted in a sleeve 17 journaled in a bearing 18 provided on a casing 19 connected with the magneto and into which the 15 armature 15 extends, this sleeve being provided beyond the bearing 18 with a pinion 20 meshing with a gear 21 connected with the rotatable element 22 of an electric-current distributor 23 of a well-known type, which latter would, in practice, be connected up with the magneto 13 and the sparking devices (not shown) for the cylinders for properly timing the sparking in the latter. 20 The outer end of the sleeve 17 is counterbored to afford an annular socket 24 into which a sleeve 25 surrounding the shaft 16 and splined thereon, extends. The outer shouldered end of the sleeve 25 is formed 25 with a peripheral groove 26 containing a ring 27 provided with radially-extending lugs 28 for attachment to a yoke (not shown), through the medium of which the sleeve 25 may be moved longitudinally of 30 the shaft 16 and sleeve 17, the inner end of the sleeve 25 containing a pin 29 which extends into a cam-slot 30 in the outer end of the sleeve 17, whereby, upon shifting the sleeve 25 longitudinally of the shaft 16, the 35 sleeve 17 will be rotated independently of the shaft 16 in a direction depending upon the direction in which the sleeve 25 is moved for adjusting the rotary element 22 of the distributor 23 while in operation for advancing or retarding the spark as desired 40 relative to the operation of the engine-pistons.

The inner reduced end 31 of the sleeve 17 is equipped with a disk 32 rigid therewith, 45 this disk being equipped with laterally-extending rods 33 shown as four in number and adjacent ones of which are arranged at an angle of 90° to each other. The outer ends of these rods are connected with a ring 50 34, and extending between the ring 34 and disk 32 and journaled on the rods 33 are sleeves 35, the plate 32, ring 34 and rods 33 forming a cage secured to and rotatable with the sleeve 17, which latter through the 55 medium of the pin 29, rotates with the shaft 16. Secured to the armature 15 is a disk 36 carrying a plate 37 provided with a crank-extension 38, and extending parallel with the plate 37 is a plate 39 which is provided with a crank-extension 40, the 60 plates 37 and 39 being connected together through the medium of rods 41 having sleeves 42 journaled thereon and arranged preferably at angles of 90° to each other, the outer ends of the crank-extensions 38 and 39 being connected together by a stub-shaft 43, one end of which, represented at 65 44, extends beyond the member 40, the latter being equipped with a pin 45 which is concentric with the axis upon which the armature 15 rotates and has journal bearing in a socket 46 in the inner end of the shaft 16. The armature 15 is operatively connected with the sleeve 17 through the medium of coiled springs 47 which are connected at their opposite ends with the sleeves 35 and 42 as illustrated in Fig. 2. The disk 32 is provided with a laterally-projecting pin 48 upon which a lever 49 is pivoted, this lever being connected at its free end with one end of a toggle-lever 50 formed with a rule joint 51 and journaled at its opposite end on the end 44 of the stub-shaft 43, the disk 32 being cut away as represented at 52 for the purpose of permitting 70 this connection of the toggle with the shaft 43 to be made and the movement of the parts, directly connected with the armature 15, with relation to the disk 32, for the purpose hereinafter described. Journaled on the bearing 18 adjacent to the toggle-mechanism 50 is a cam-device 53 formed of diametrically-opposed cam-portions 54, each of which is provided with a curved cam-surface 55 and a receding surface 56 intersecting the adjacent cam-surface 55, as illustrated in Fig. 5, and coöperating with the cam 53 is an arm 57 rigid with, and extending at about an angle of 90° to, the link 49, the arrangement of the parts described being such as to cause them, when in normal condition, to assume the positions illustrated in Figs. 3 and 5, the members of the toggle 50 being yieldingly held in the positions illustrated in these figures, in which the joint of the toggle extends inwardly of its points of connection with the lever 49 and shaft 44, by means of a coiled spring 58 surrounding the shaft 43, one end of this spring being secured to the member 38, and the other end engaging with one section of the toggle 50 (Fig. 5).

In the position of the parts described, the arm 57 which is provided with a curved under surface 59 extends in close proximity to the curved surface 55 of one of the cam-portions 54 of the cam 53 (Fig. 5), whereby, when the described parts connecting the armature 15 with the sleeve 17 are rotated through the medium of the shaft 16, the arm 57 will be caused to ride upon the surface 55 and be tilted upwardly to the left in Fig. 5 for the purpose hereinafter described, the cam 53 being held against rotation to the right in Fig. 5 through the medium of a dog 130

60 journaled on a pin 61 fixed in an end-wall 62 of the casing 19 and yieldingly pressed downwardly by a spring 62^a, this dog being adapted to engage with the adjacent one of shoulders 63 provided on a face of the cam 53. The dog 60 operates to cause the cam 53, to all intents and purposes, to be rigid with the bearing 18 when the rotary parts of the device are rotated to the right in Fig. 1, but permits the cam 53 to rotate to the left in Fig. 5 in the event of force exerted against the cam tending to move it in this direction.

The operation of the described mechanism is as follows: Rotation of the shaft 16 to the right in Fig. 5, as for instance in the cranking of the engine geared to this shaft and in connection with which the magneto is employed, operates to rotate the sleeve 17, and the cage, formed of the disk 32, ring 34, rods 33 and sleeves 35, to the right in Fig. 1, and as the plates 36, 37 and 39 carried by the armature 15 are connected with the cage through the medium of the springs 47, rotation of the cage as described operates to also rotate the armature 15. In the initial movement of the shaft 16 as described, the arm 57 is caused to ride upon the adjacent cam-portion 54, with the result of rocking the lever 49 to the left in Fig. 3 and consequently, through the medium of the toggle 50, retarding the movement of the armature 15 to the right in Fig. 3, relative to the movement of the shaft 16 and the cage connected therewith, thereby placing the springs 47 under tension. The relative retarded movement of the armature 15 as described continues until the free end of the arm 57 (which latter, in its final movement against the cam-portion 54 of the cam 53, assumes the position illustrated in Fig. 7, passes the end of said cam-portion, whereupon, under the action of the springs 47, it swings inwardly, thereby permitting the springs 47, which form elastic means connecting the armature to the shaft 16, to freely exert on the parts carried by the armature 15 the power stored in said springs during the movement of the arm 57 against the cam-portion 53 as hereinbefore described. The manifest result of the operation of the parts as described is that of causing the armature in its initial movement to move slower than the shaft 16, in which movement power is stored in the springs 47, which retarded movement of the armature 15 is followed by a momentary acceleration of the armature under the action of the stored power in these springs, thus resulting in the production of a current of relatively great intensity for producing a powerful spark at the electrical terminals in the engine, in the particular illustrated embodiment of my invention the retarding and acceleration of the armature 15 occurring

twice in each revolution of the shaft 16 by reason of the provision of two similar cam-ports 54.

It is desirable that, after the engine has attained a certain speed, the armature 15 be driven at a speed corresponding to that of the shaft 16, as distinguished from the variable speed described, this being effected through the medium of the toggle 50, which latter, under the action of centrifugal force 75 in opposition to the spring 58, is caused to be moved to the position represented in Fig. 8, in which the arm 57 is swung to a position in which it clears the cam-ports 54 in the rotations of the shaft 16, and thus a 80 comparatively steady pull is exerted through the medium of the springs 47, upon the described rotary parts carried by the armature 15, a pin 63 carried on the outer face of the disk 32 operating to limit the 85 movement of the toggle 50 under the action of centrifugal force, as stated.

From the foregoing description, it will be understood that the cam 53 is free to be turned to the left in Fig. 5, this feature of 90 my construction being desirable as it prevents impairment of the parts of the mechanism in the event of the rotation thereof to the left in Fig. 5, as would likely be the case in the event of back-fire of the engine, under 95 which conditions the arm 57, in its retrograde movement, would engage with the adjacent one of the cam-ports 54 and operate to freely turn the cam 53 to the left in Fig. 5.

It will be understood that where the magneto is used in connection with an internal-combustion engine which in its use is not required to be operated rapidly, the feature of automatically throwing the armature-retarding means out of operative position need not be employed, this feature being only desirable where the engine in connection with which the mechanism is used, is caused to be driven at a speed sufficient to 110 produce the desired spark when the magneto-armature has rotary movement corresponding to that of the drive-element therefor, as distinguished from alternate retarded and accelerated movement.

The feature of driving the distributor 23 from the shaft 16, as distinguished from driving it from the magneto-armature, is of great advantage in mechanism of this character, as the rotary element of the distributor is rotated correspondingly with the shaft 16, as distinguished from the alternate retarded and accelerated movements it would have if operated from the armature 15, and thus noise, undue wear of the distributor in its driving connections, and such operation of the distributor as will produce improper timing of the spark controlled from the distributor, is avoided. Furthermore, this arrangement is advantageous as 130

less powerful accelerating means are required for operating the movable member of the magneto than in those cases where the distributor is likewise intermittently accelerated.

The arrangement of the springs as described serves to balance them relative to each other and thus wear of the bearings for the rotating parts of the mechanism is reduced to the minimum.

While I have illustrated and described springs as forming the elastic means for connecting the armature 13 with the shaft 16, I do not wish to be understood as intending 15 to limit my invention to the use of springs, as any other suitable means connecting the shaft 16 with the armature 15 and operating to store energy when the armature is retarded relative to the shaft 16, may be employed.

While I have illustrated a particular embodiment of my invention, I do not wish to be understood as intending to limit my invention to such construction, as the same 25 may be variously modified and altered without departing from the spirit of my invention.

What I claim as new, and desire to secure by Letters Patent, is—

30 1. The combination with a magneto and a drive-member therefor, of elastic means connecting the rotary member of said magneto with said drive-member, means connecting together said rotary member and said 35 drive-member and operating, when actuated, to momentarily retard the movement of said rotary member with relation to said drive-member in opposition to said elastic means, and means for actuating said rotary-member-retarding means, for the purpose set forth.

2. The combination with a magneto and a drive-member therefor, of elastic means operatively connecting the rotary member of 45 said magneto with said drive-member, means connecting together said rotary member and said drive-member and movable therewith and operating, when actuated, to momentarily retard the movement of said rotary member relative to said drive-member in opposition to said elastic means, and a cam-device extending into the path of movement of said rotary-member-retarding means for actuating the latter, for the purpose set forth.

3. The combination with a magneto and a drive-member therefor, of elastic means operatively connecting the rotary member of said magneto with said drive-member, means connecting together said drive-member and said rotary member and movable therewith and operating, when actuated, to momentarily retard the movement of said rotary member relative to said drive-member in opposition to said elastic means, said

last-named means including a rock-arm operating, when actuated, to return the movement of said rotary member, and a relatively stationary cam interposed in the path of movement of said rock-arm, for the purpose set forth.

4. The combination with a magneto and a drive-member therefor, of elastic means operatively connected with the rotary member of said magneto and with said drive-member and movable therewith, means connecting together said rotary member and said drive-member for momentarily retarding the movement of said rotary member relative to said drive-member and in opposition to said elastic means comprising a pivotally-supported lever operatively connected with said drive-member, a link-device connected with said lever and operatively connected with said rotary member, an arm operatively connected with said lever, and means extending into the path of movement of said arm for actuating the latter, for the purpose set forth.

5. The combination with a magneto and a drive-member therefor, of elastic means operatively connected with the rotary member of said magneto and with said drive-member and movable therewith, means operatively connected with said rotary member and with said drive-member for momentarily retarding the movement of said rotary member relative to said drive-member and in opposition to said elastic means comprising a pivotally-supported lever operatively connected with said drive-member, toggle-members operatively connected with said first-named lever and with said rotary member, an arm operatively connected with said first-named lever, and means extending into the path of movement of said arm for actuating the latter, for the purpose set forth.

6. The combination with a magneto and a drive-member therefor, of elastic means connecting the rotary member of said magneto with said drive-member, and means for retarding the movement of said rotary member relative to said drive-member and in opposition to said elastic means including a lever pivotally supported on said drive-member and eccentric to the axis about which said drive-member and rotary member rotate and means for operating said lever.

7. The combination with a magneto and a drive-member therefor, of elastic means connecting the rotary member of said magneto with said drive-member, and means operatively engaging with said rotary member and said drive-member for retarding the movement of said rotary member relative to said drive-member and in opposition to said elastic means comprising a lever pivotally supported eccentric of the axis about which said rotary member and drive-member

- ber rotate, a link, an arm through the medium of which said lever is actuated, and means extending into the path of movement of said arm for actuating the latter, for the purpose set forth.
8. The combination with a magneto and a drive-member therefor, of a pin operatively connected with said drive-member and eccentric to the axis of rotation of the latter, a pin operatively connected with the rotary member of said magneto and eccentric to its axis of rotation, elastic means normally radially-disposed and connected with said pins and through the medium of which said rotary member is driven from said drive-member, and means for momentarily retarding the movement of said rotary member relative to said drive-member and in opposition to said elastic means, for the purpose set forth.
9. The combination with a magneto and a drive-member therefor, of a pin operatively connected with said drive-member and eccentric to the axis of rotation of the latter, a pin operatively connected with the rotary member of said magneto and eccentric to its axis of rotation, a normally radially-disposed spring connected at opposite ends with said pins and through the medium of which said rotary member is driven from said drive-member, and means for momentarily retarding the movement of said rotary member relative to said drive-member and in opposition to said spring, for the purpose set forth.
10. The combination with a magneto and a drive-member therefor, of a pin operatively connected with said drive-member and eccentric to the axis of rotation of the latter, a pin operatively connected with the rotary member of said magneto and eccentric to its axis of rotation, said pins extending normally in a straight line radially of said shaft; elastic means connecting said pins and through the medium of which said rotary member is driven from said drive-member, and means for momentarily retarding the movement of said rotary member relative to said drive-member and in opposition to said elastic means, for the purpose set forth.
11. The combination with a magneto and a drive-member therefor, of a rotatable disk driven from said drive-member and carrying a pin projecting from its face, a pin extending laterally from and eccentric with the rotary member of said magneto, a normally radially-disposed spring connected at opposite ends with said pins and through the medium of which said rotary member is driven from said drive-member, and means for momentarily retarding the movement of said rotary member relative to said drive-member and in opposition to said spring, for the purpose set forth.
12. The combination with a magneto and a drive-member therefor, of a rotatable disk operated by said drive-member, elastic means operatively connected with said disk and with the rotary member of said magneto and operating to connect said disk and said rotary member together, means connecting together said disk and said rotary member and operating, when actuated, to momentarily retard the movement of said rotary member relative to said disk and in opposition to said elastic means, and means for actuating said last-named means, for the purpose set forth.
13. The combination with a magneto and a drive-member therefor, of elastic means operatively connected with the rotary member of said magneto and with said drive-member, means operatively connected with both said drive-member and with said rotary member, operating, when actuated, to momentarily retard the movement of said rotary member relative to said drive-member in opposition to said elastic means, and means for intermittently operating said rotary-member-retarding means, said last referred to means being movable, under the action of centrifugal force, from operating to non-operating position when the speed of said drive-member exceeds a predetermined speed.
14. The combination of a magneto, a casting provided with a journal-bearing, a drive-member journaled in said bearing, a cage operatively connected with said drive-member and formed of a ring and a disk spaced apart and rods connecting said ring and disk together, a rotary member secured to the armature of said magneto to rotate therewith and extending into said cage, said rotary member being formed with cross-rods, springs connected with the cross-rods on said cage and the cross-rods on said armature, means operatively connected with said cage and with said rotatable member operating, when actuated, to momentarily retard the movement of said armature relative to said drive-member and in opposition to said springs, a cam-device journaled on said bearing and extending into the path of movement of said armature-retarding means, and means for preventing said cam-device from rotating in the direction of normal movement of said cage.
15. The combination with a magneto and a drive-member therefor, of elastic means connecting the rotary member of said magneto with said drive-member, means, including collapsible toggle-members, operatively connected with said drive-member and with said rotary member for momentarily retarding the movement of said rotary member relative to said drive-member in opposition to said elastic means, and means for intermittently operating said ro-

tary-member-retarding means, for the purpose set forth.

16. The combination with a magneto and a drive-member therefor, of elastic means operatively connecting the rotary member of said magneto with said drive-member, means operating, when actuated, to momentarily retard the movement of said rotary member relative to said drive-member and in opposition to said elastic means, a rotatably-mounted cam-device for actuating said retarding-means, and means for holding said cam-device against forward rotation, but permitting it to be rotated in the opposite direction for the purpose set forth.

17. The combination with a magneto and a drive-member therefor, of elastic means operatively connecting the rotary member of said magneto with said drive-member, means operatively connected with said drive-member and with said rotary member and operating, when actuated, to retard the movement of said rotary member relative to said drive-member in opposition to said elastic means, a rotatably-mounted cam-device extending into the path of movement of said rotary-member-retarding means and operating to actuate the latter when engaged thereby, and means for holding said cam-device against forward rotation, for the purpose set forth.

18. The combination of a magneto, a drive-member, means for driving the rotary member of said magneto from said drive-member with an alternately retarded and accelerated movement relative to the movement of said drive-member, an electric-current distributor, formed with a rotary element, and means for communicating to said rotary element a movement corresponding with the movement of said drive-member.

19. The combination of a magneto, a drive-member, means for driving the rotary member of said magneto from said drive-member with an alternately retarded and accelerated movement relative to the movement of said drive-member, an electric-current distributor formed with a rotary element, and means for driving the rotary member of said distributor direct from said drive-member as distinguished from driving it through the rotary member of said magneto, whereby the rotary member of said distributor is given a movement corresponding with the movement of said drive-member.

20. The combination with a magneto and a drive-member therefor, of elastic means connecting the rotary member of said magneto with said drive-member, means, including outwardly collapsible toggle-members, operatively connected with said drive-member and with said rotary member for momentarily retarding the movement of said rotary member relative to said drive-member

ber in opposition to said elastic means, and means for intermittently operating said rotary-member-retarding means, for the purpose set forth.

21. The combination with a magneto and a drive-member therefor, of diametrically-opposed normally radially-extending elastic connections between the rotary member of said magneto and said drive-member, and means for momentarily retarding the movement of said rotary member relative to said drive-member and in opposition to the action of said elastic connections.

22. The combination with a magneto and a drive-member therefor, of diametrically-opposed normally radially-extending springs connected with the rotary member of said magneto and with said drive-member, and means for momentarily retarding the movement of said rotary member relative to said drive-member and in opposition to the action of said springs.

23. The combination with a magneto and a drive-member, of elastic connections balanced in normal condition between the rotary member of said magneto and said drive-member, and means for momentarily retarding the movement of said rotary member relative to said drive-member and in opposition to the action of said elastic connections.

24. The combination with a magneto and a drive-member, of normally radially-disposed springs in balanced condition connecting the rotary member of said magneto with said drive-member, and means for momentarily retarding the movement of said rotary member relative to said drive-member and in opposition to the action of said springs.

25. The combination with a magneto and a drive-member therefor, of elastic means operatively connecting the rotary member of said magneto with said drive-member, means operating, when actuated, to momentarily retard the movement of said rotary member relative to said drive-member and in opposition to said elastic means, a rotatable cam for actuating said retarding means concentric of the axis upon which said drive-member rotates, and means for holding said cam against forward rotation, for the purpose set forth.

26. The combination with a magneto and a drive-member therefor, of elastic means connected with the rotary member of said magneto and with said drive-member, means for momentarily retarding the movement of said rotary member relative to said drive-member and in opposition to said elastic means, including an arm, and a cam in the path of movement of said arm for actuating said retarding means, the co-operating surfaces of said cam and arm being curved and describing arcs of substantially the

- same radius, whereby a broad bearing of said arm on said cam is afforded.
27. The combination with a magneto and a drive-member therefor, of elastic means connecting the rotary member of said magneto with said drive-member, means, including toggle-members operatively connected with said drive-member and with said rotary member for momentarily retarding the movement of said rotary member relative to said drive-member in opposition to said elastic means and means on said toggle-members for preventing them from collapsing in one direction, and means for intermittently operating said rotary-member-retarding means, for the purpose set forth. 70
28. The combination with a magneto and a drive-member therefor, of elastic means connecting the rotary member of said magneto with said drive-member, means, including toggle-members operatively connected with said drive-member and with said rotary member for momentarily retarding the movement of said rotary member relative to said drive-member in opposition to said elastic means, means on said toggle for preventing it from collapsing in one direction, and means for yieldingly holding said toggle-members from collapsing in the opposite direction, and means for intermittently operating said rotary-member-retarding means, for the purpose set forth. 75
29. The combination with a magneto and a drive-member therefor, of elastic means connecting the rotary member of said magneto with said drive-member, means, including toggle-members operatively connected with said drive-member and with said rotary member for momentarily retarding the movement of said rotary member relative to said drive-member in opposition to said elastic means and means for holding said toggle-members in extended condition against collapsing when said drive-member is rotating below a predetermined speed, and means for intermittently operating said rotary-member-retarding means. 80
30. The combination with a magneto and a drive-member therefor, of elastic means connecting the rotary member of the magneto with the said drive-member, toggle-members having pivotal operative connection with said drive-member and with said rotary member eccentrically of the axis about which said members rotate, means connected with said toggle-members operating, when actuated, to retard the movement of the latter and said rotary member relative to said drive-member and in opposition to said elastic means, means operating to hold the members of said toggle against collapsing in one direction and to cause the joint between said toggle-members to ex- 85
- tend intermediate the axis about which said drive-member rotates and a line passing through the points of support for said toggle-members, and means for actuating said toggle-actuating means. 90
31. The combination with a magneto and a drive-member therefor, of elastic means connected with said drive-member and the rotary member of said magneto, means for momentarily retarding the movement of said rotary member relative to said drive-member and in opposition to said elastic means, an electric-current distributor formed with a rotary member, means for driving the rotary member of said distributor from said drive-member, and means for adjusting the position of said last-named means relative to said drive-member. 95
32. The combination with a magneto and a drive-member therefor, of elastic means connected with said drive-member and the rotary member of said magneto, means for momentarily retarding the movement of said rotary member relative to said drive-member and in opposition to said elastic means, an electric-current distributor formed with a rotary member, a rotatable member through the medium of which the rotary member of said distributor is actuated, and shiftable means for driving said rotatable member from said drive-member operating, when shifted, to change the angular position of said rotatable member about its axis relative to said drive-member. 100
33. The combination with a magneto and a drive-member therefor, of elastic means connected with said drive-member and the rotary member of said magneto, means for momentarily retarding the movement of said rotary member relative to said drive-member and in opposition to said elastic means, an electric-current distributor formed with a rotary member, a sleeve rotatably mounted on said drive-member, means operated by said sleeve for rotating the rotary member of said distributor, a shiftable member rotatable with said drive-member, means on said shiftable member for engaging with and driving said sleeve and operating, when said shiftable member is shifted, to vary the angular position of said sleeve about its axis relative to said drive-member, and means for shifting said shiftable member. 105
34. The combination with a magneto and a drive-member therefor, of a normally radially-disposed spring connecting the rotary member of said magneto with said drive-member, and means for momentarily retarding the movement of said rotary member relative to said drive-member and in opposition to the action of said spring. 110
35. The combination with a magneto, of a rotatable member, elastic means connected with said rotatable member and the rotary 115

- member of said magneto, a driving element for said rotatable member, means for adjusting said rotatable member relative to said driving element, means for momentarily retarding the movement of the rotary member of said magneto relative to said rotatable member and in opposition to said elastic means, an electric current distributor formed with a rotary member, and means for driving the rotary member of said distributor from said rotatable member.
36. The combination with a magneto, of a rotatable member, elastic means connected with said rotatable member and the rotary member of said magneto, a driving element for said rotatable member, means for axially adjusting said rotatable member relative to said driving element, means for momentarily retarding the movement of the rotary member of said magneto relative to said rotatable member and in opposition to said elastic means, an electric current distributor formed with a rotary member, and means for driving the rotary member of said distributor from said rotatable member.
37. The combination with a magneto, of a rotatable member, elastic means connected with said rotatable member and the rotary member of said magneto, a driving element for said rotatable member, means for adjusting said rotatable member relative to said driving element, means for momentarily retarding the movement of the rotary member of said magneto relative to said rotatable member and in opposition to said elastic means, an electric current distributor formed with a rotary member, and means for driving the rotary member of said distributor from said rotatable member.
38. The combination with a magneto and a drive-member therefor, of an elastic connection between the rotary member of said magnet and said drive-member, and means for momentarily retarding the movement of said rotary member relative to said drive member and in opposition to the action of said elastic connection, said elastic connection being constructed and arranged to yieldingly resist the movement of said rotary member beyond normal position while traveling under the impetus transmitted to it by the operation of said elastic connection.
